[57] CLAIM

The ornamental design for a combined treatment table and cabinet assembly, as shown and described.

DESCRIPTION

FIG. 1 is a side elevational view of a combined treatment table and cabinet assembly showing my new design;

FIG. 2 is a right end view thereof;

FIG. 3 is a left end view thereof;

FIG. 4 is a top plan view thereof; and

FIG. 5 is an under side view thereof.
The opposite side of that shown in FIG. 1 is a mirror image.
